UNITED STATES PATENT OFFICE.

ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

CASE.

Application filed July 5, 1921. Serial No. 482,633.

To all whom it may concern:

Be it known that I, ELMER L. SCHUMACHER, a citizen of the United States, residing at Southbridge, in the county of Worcester and 5 State of Massachusetts, have invented certain new and useful Improvements in Cases, of which the following is a specification.

This invention relates to improvements in cases and has particular reference to cases 10 formed from zylonite, celluloid or other non-metallic material.

One of the principal objects of the present invention is the provision of a novel and improved construction of case formed from 15 zylonite or other non-metallic material which will be formed with a continuous hinge so that the case shall be substantially dust proof and which shall be provided with improved means for holding the case in closed 20 position.

A further object of the invention is the provision of a novel and improved case in which both the interior and exterior shall be substantially smooth in finish so that no 25 covering or lining for the case is required.

Other objects and advantages of my improved construction of case should be readily apparent by reference to the following specification taken in connection with the accompanying drawings, and it will be understood 30 that I may make any modifications in the specific details of construction shown and described within the scope of the appended claims without departing from or exceeding 35 the spirit of my invention.

Figure I is a perspective view of the rear of my case in closed position.

Figure II is a front view of the case 40 opened, illustrating the interior thereof.

Figure III is a sectional view as on the line III—III of Figure II.

Figure IV is a sectional view taken as on the line IV—IV of said figure.

In the drawings, the numeral 1 designates 45 the body portion of my improved case formed or shaped from suitable composition material, while the numeral 2 designates the cover section thereof. Uniting these parts is my improved hinge comprising the flat or sheet portion 3 secured to the rear of the body portion of the case, and having an enlarged apertured portion 4 through which passes the hinge wire 5. The cover section 50 is provided with a similar sheet portion 6

and enlarged apertured portion as 7 also 55 receiving the hinge wire 5. These portions 4 and 7 may if desired be formed by molding the material when hot and subsequently drilling so that there will be no liability of the opening up of the hinge, or under some 60 circumstances may be made by rolling the edge of sheet stock or by doubling thin stock to form the rounded hinge receiving portion and securing the body together so that the plate or sheet portions 3 and 6 will in that 65 case be laminated or made up of two layers of the material. These portions 3 and 6 are secured respectively to the body and to the cover of the case by the employment of a suitable adhesive which will serve to unite 70 the plate portion and top into a substantially unitary structure.

The hinge wire 5 is formed from a suitable spring material and has its ends bent in the L portions or termini 8 and 9 which 75 fit respectively beneath the flap or pocket members 10 and 11, which like the hinge portions are cemented or similarly suitably secured to the body and cover portions and serve to receive, hold and conceal the ends 80 of the springs, being rounded out as at 12 for that purpose so that the springs may be snapped into the pockets thus provided and the structure when complete will present no rough spring ends or edges to catch on 85 either glasses or the clothing, handkerchief, or the like, of the user, but on the other hand will present a neat and attractive appearance. The spring hinge member ends are so related to each other as to tend to hold the 90 lid in closed position so that opening it to take out the glasses will twist the resilient spring portion, which when released will spring back into closed position.

I claim:

1. A case comprising a body, an eyeglass receiving compartment, the forward edge of the body having an overlying wall, a cover for the body adapted to engage over the overlying wall when closed, certain diagonally opposite portions of the corresponding adjacent edges of the body and the cover respectively having pockets formed by members cemented thereto, interconnecting hinge members carried by the body and cover respectively and having tubular rolls registering axially, and a single straight spring pintle passing through said axially 100 105

registering rolls, said pintle having its end portions bent laterally in corresponding directions, each bent end portion engaging one of said pockets, said bent end portions being 5 normally parallel, whereby the body of the spring pintle twists upon opening the cover, thereby resulting in the cover automatically closing in contact with the overlying wall.

2. A case provided with an eyeglass re-
10 ceiving compartment and comprising a body and a cover therefor, the corresponding ad-
jacent edges of the cover and the body re-
spectively at diagonally opposite portions
thereof having pocket members adhesively
15 fastened thereto, interconnected hinge mem-
bers carried by the body and cover respec-
tively and having tubular rolls registering

axially, and a single straight spring pintle
passing through said axially registering
rolls, said pintle having its end portions 20
bent laterally in corresponding directions,
each bent portion engaging one of said
pockets, said bent end portions being nor-
mally parallel whereby the body of the
spring pintle twists upon opening the cover,
thereby resulting in the cover automatically
closing. 25

In testimony whereof I have affixed my
signature, in presence of two witnesses.

ELMER L. SCHUMACHER.
